UNITED STATES PATENT OFFICE.

WILLIAM MYRON KECK, OF COALINGA, CALIFORNIA.

PIPE-WRENCH.

1,125,554.

Specification of Letters Patent.

Patented Jan. 19, 1915.

Application filed June 3, 1914. Serial No. 842,675.

To all whom it may concern:

Be it known that I, WILLIAM M. KECK, a citizen of the United States, and a resident of Coalinga, in the county of Fresno and State of California, have invented a new and Improved Pipe-Wrench, of which the following is a full, clear, and exact description.

This invention relates to tools or implements for manipulating heavy pipes or well tubing, and has particular reference to certain details of improvements in these devices adapting them for a larger range of operation and easier manipulation than may be had by other devices commonly in use.

Among the objects of the invention, more definitely stated, is to provide a chain wrench for operation upon heavy pipes or well casings, which is readily adjustable for application to either a pipe or a pipe coupling and for operation in the direction to screw on or unscrew the part without turning the wrench over.

The foregoing and other objects of the invention will hereinafter be more fully described and claimed and illustrated in the drawings forming a part of this specification in which like characters of reference indicate corresponding parts in all the views, and in which—

Figure 1 is a side elevation of my improvement shown as applied to the coupling of a vertical well casing or a large pipe; Fig. 2 is a plan view of the same, the pipe coupling being in section; Fig. 3 is a horizontal sectional view of the device applied to the coupling, the direction of rotation being reversed from that of Fig. 2; and Fig. 4 is a plan view corresponding to Fig. 2, showing the device adapted to the pipe instead of the coupling.

The several parts of the device may be made of any suitable materials, and the relative sizes and proportions, as well as the general design of the mechanism, may be varied to a considerable extent without departing from the spirit of the invention hereinafter more fully set forth and specifically claimed.

Referring more particularly to the drawings, I show at 10 a lever to the head of which is connected a hanger loop 11 of any suitable character whereby the apparatus may be suspended by means of a connection 12 from any suitable overhead support (not shown). The head of the lever is provided

with a vertical hole 13 and with a nose 14 extending directly in alinement with the central axis of the lever. Shoulders 15 are provided at the base of the nose, the faces of the shoulders being directed toward the point of the nose, but the shoulders on opposite sides of the head are arranged at an obtuse angle 16 to each other.

At 17 I show a pair of bars of the same size and form, the same being provided with registering holes 18 at the free ends of the bars. In the ends of the bars opposite the holes 18 is journaled a swiveled knuckle 20 for free rotation between the bars, said knuckle being secured in place by any suitable means. The knuckle 20 is tapped through its center at right angles to its axis of rotation, and secured therein is a take-up screw 21 of the anchor link 22 of the gripping chain.

The chain may be of any suitable construction, but is shown herein as comprising alternate block and plate links 23 and 24. The first pair of plate links are pivoted at 25 to the head of the anchor link 22. The plate links at the outer end of the chain are loosely pivoted at 26 on opposite sides of a die block 27. The pivotal connection with the die block is through a slot 28 arranged at right angles to the axis of the die block.

As shown in the drawings, especially in comparing Figs. 2 and 4, it will be noted that the die block and the chain links are each formed with concave edges or faces adapted to bear against the pipe or coupling elements, the concavities on opposite sides or edges being formed on different arcs according to the standard sizes of pipes or couplings. In other words, the die block has a concave face P adapted to conform to the circumference of the pipe, and on the opposite side or face the concavity C corresponds to the radius of the coupling. Likewise the edges p of the links correspond to the radius of the pipe, and c indicates the opposite edges having the larger radius.

Each concave face of the die block is preferably fitted with a biting tooth 29 for direct engagement with the curved surface of the pipe or coupling. The end of the die block opposite the slot 28 is provided with a vertical pin 30 spanning a bifurcation adapted to admit the nose 14 of the lever head, the nose being designed to operate directly against the pin 30 and the ends of

the die block adjacent thereto are adapted to roll upon the shoulders 15 above described.

As shown in Figs. 1 and 2, the implement is arranged in gripping engagement with the coupling and adapted to turn or screw the coupling upon the next lower pipe section. In this arrangement a detachable pin 31 is projected through the holes 18 of the bars 17 and the hole 13 of the lever head. The die block and links, as shown in Fig. 2, are arranged with the concavities C and c adjacent the coupling. With the bifurcated end of the die block projecting between the bars 17 and with the nose 14 introduced into engagement with the inner face of the pin 30, the swinging of the lever in the direction of the arrow a will cause the chain and die block to grip the coupling and turn it in a clockwise direction, as shown in Fig. 2. In order to unscrew the coupling, the only change required to be made in the implement is to swing the lever free from the die block and then, by grasping the die block in one hand, the operator straightens the chain and then gives the die block and chain a half rotation around the longitudinal axis of the chain, the pivotal connection between the anchor link 22 and the swiveled knuckle 20 with each other and with the bars 17 permitting such rotation. It is then an obvious expedient to apply the chain and die block to the coupling, as shown in Fig. 3, when a movement of the lever in the direction of the arrow b will operate to unscrew the coupling. The concavities C and c in this arrangement will again be arranged in connection with the curved surface of the coupling. It will be noted, however, that the heavy lever 10 and the bars 17 connected thereto are not turned over nor reversed but remain suspended as before.

From the plan views shown it will be observed that the several links are connected each to each by pivot pins that are off center or far enough to one side of the longitudinal axis of the chain to provide for the fitting of the chain to either the pipe or the coupling simply by turning it over through an angle of 180 degrees. In Fig. 2, for instance, the chain is fitted to the coupling and hence the pivot pins are comparatively close to the sides c of the chain links. In Fig. 4, however, the chain, without any other change except the turning around on its longitudinal axis, as above stated, is fitted to the pipe. It will be observed, therefore, that the pin 31 will not require to be changed or withdrawn for the ordinary change of the wrench to fit either the pipe or the coupling of any standard size. The manner of connecting the anchor link 22 to the knuckle 20 provides for such delicacy of adjustment as may be necessary to fit the

chain to varying diameters of the same standard size of pipe.

At 32 I show a chain of any suitable light construction having a hook 33 detachably connected to the die block 27 in a hole 34 along either edge thereof. The chain is adapted to coöperate at its intermediate portion with a claw 35 whereby, when the slack is taken up when the chain is clamped to the pipe or coupling, the light chain 32 will serve to return the main wrench chain into a new gripping position when the lever 10 is reversed for a new grip. But for the chain 32 and its connection to the die block, the weight of the main chain would cause the parts to become separated and the main chain would probably drop out of position when the lever is reversed after each reciprocation.

Having thus described my invention, I claim as new and desire to secure by Letters Patent:—

1. The herein described pipe wrench comprising a lever having a nose projecting from the end thereof directly in line with its longitudinal axis, a gripping chain, a pair of bars pivoted to opposite sides of the lever, a swivel connecting one end of the chain to the bars, and a die block connected to the other end of the chain and adapted to coöperate with said nose for turning the pipe element in either direction.

2. The herein described pipe wrench comprising, in combination, a lever having a nose projecting from the end thereof, a pair of bars pivoted on opposite sides of the lever, a chain connected at one end by means of a swivel to the bars, and a die block secured to the other end of the chain, said die block being adapted to extend between the bars aforesaid and having a pin for coöperation with said nose, said die block and chain links being provided along opposite edges with concavities of different curvatures according to the application thereof to a pipe or a coupling.

3. The herein described pipe coupling comprising, in combination, a lever having a head and a nose projecting longitudinally from the head in the axis of the lever, said head having a pivot hole therethrough, a pair of bars on opposite sides of the lever head, each bar having a pair of end holes therethrough, a pivot pin projecting through said head hole and certain of the holes of the bars at the outer ends thereof, a knuckle pivoted in the holes at the outer ends of the bar, a chain having an end link constituting an anchor and adjustably connected in said knuckle, a die block connected to the other end of the chain and adapted to extend between the bars aforesaid, said lever nose being adapted to interlock with said die block, said chain links and die block each being provided with concave

edges, the concavities on one side being of larger radius than those on the other side whereby the chain and die block are fitted to either a pipe of standard size or a coupling therefor, and means to prevent the accidental separation of the parts on the reverse movement of the lever.

4. In a chain pipe wrench, the combination of a lever, a main chain having links 10 pivoted together at points at one side of the longitudinal axis thereof, the edges of the links on one side being of a larger radius than those on the other side, the pivots being arranged nearer the edges of larger radius, means pivotally connecting one end of the chain permanently to the lever, and a die block connected to the other end of the chain and having loose interlocking

connection with the end of the lever, substantially as set forth.

5. In a chain-pipe wrench, the combination of a lever, a main chain, means pivotally connecting one end of the chain securely to the lever, a die block loosely pivoted to the other end of the chain and adapted to interlock with the end of the lever, and a flexible member detachably connected to the die block and adjustably connected to the lever, substantially as set forth.

In testimony whereof I have signed my name to this specification in the presence of two subscribing witnesses.

WILLIAM MYRON KECK.
